UNITED STATES PATENT OFFICE.

LUCIUS P. BELL, OF SCHENECTADY, NEW YORK.

DESIGN FOR STANDARDS FOR WEIGHING-SCALES.

Specification forming part of Design No. **11,244**, dated June 10, 1879; application filed May 19, 1879.
[Term of patent 7 years.]

To all whom it may concern:

Be it known that I, LUCIUS P. BELL, of Schenectady, in the county of Schenectady and State of New York, have originated and designed a Standard for Weighing-Scales, of which the following is a full, clear, and exact description, reference being had to the accompanying drawing, making part of this specification.

A represents a pair of weighing-scales, which may be of any construction. Upon the standard B, supporting said scales, which said standard is usually and preferably cast of iron, brass, or other metal, I form in relief a rep-

resentation of a bell. The standard itself may also be formed or molded in the shape of a bell; but this is not necessary, inasmuch as my invention consists, essentially, in ornamenting a scale-standard with the representation of a bell, as shown in the accompanying illustration.

What I claim is—

A design for scale-standards, consisting of the representation of a bell, as set forth.

LUCIUS P. BELL.
